DYE FLUID DISPENSING METER

Harry L. Stafford, Alexandria, Va., assignor to the
United States of America as represented by the
Secretary of Agriculture

Application January 2, 1951, Serial No. 204,058

3 Claims. (Cl. 222—477)

(Granted under Title 35, U. S. Code (1952),
sec. 266)

1
The invention herein described may be manufactured and used by or for the Government of the United States of America for governmental purposes throughout the world without the payment to me of any royalty thereon.

This invention relates to an apparatus for dispensing a liquid, such as aqueous dye, in uniform amounts. It particularly relates to a device for automatically modifying or substantially controlling, or substantially halting, the flow of liquid through an outlet by the movement of a buoyant shuttle to the outlet.

An object of this invention is an apparatus readily calibrated and adjusted to deliver a predetermined amount of liquid.

One embodiment of the invention is illustrated in the drawing, in which:

Figure 1 is a three dimensional view of the assembled apparatus;

Figure 2 is a view in elevation, partly in section, of the shuttle cylinder;

Figure 3 is a vertical section of the lower end of the shuttle and the shuttle cylinder.

Liquid from tank 1 flows into chamber 2 through a lower opening (not shown) in the plate 3, near the lower edge. The function of chamber 2 is to provide a uniform head of liquid for the metering and dispensing apparatus. From chamber 2 the liquid flows through perforations 4 into pipe 5. During operation of the apparatus, when delivering liquid, the upper end of pipe 5 is open to the atmosphere. Air enters the upper end of pipe 5 and passes through openings 6 into chamber 2, as the contents of the chamber are dispensed. A cap 7 is conveniently used when chamber 2 is filled initially.

Pipe 5 is welded to chamber 2 and extends below it to provide a coupling end for attachment of the shuttle cylinder 8. Cylinder 8 is a pipe having a one inch inside diameter. In the lower end of 8 is fitted a shuttle seating number 9. Conventional coupling means 10, 11, 12, 13 is employed to attach hose 14. The liquid passes through hose 14 and is dispensed by spring valve faucet 15.

The shuttle 16 is conveniently made of seamless aluminum tubing having an outside diameter of three-fourths of an inch. As shown in Figure 3, the surface of the tubing is corrugated by grooves cut therein. The two faces of each groove are 90° and 60° to the axis of the tube. The depth of the groove is .025 inch. These corrugations decrease the weight of the tube, thus increasing its buoyancy, and also increase the friction between the shuttle wall and the fluid

which by-passes the valve during its descent. The shuttle is made buoyant by cork filling 17. The lower end may be weighted, for example by means of screw 18, for added stability. Notches 19 in the lower end of the shuttle are provided for the purpose of bleeding the chamber 8 to counteract the suction in the hose 14 which occurs during the interval between the impact of the shuttle upon its seat 9 and the closing of the hose valve 15. This releases the shuttle and permits it to rise and complete its cycle. The 60 degree angle of the seat sidewall 90 serves to correct any erratic position of the valve, by guiding it into positive contact with the seat facing which is cut at 90 degrees to the axis.

Rod 20 is adjusted in place to provide a stop 21 for the shuttle. The distance the shuttle travels is thus determined. Therefore, the position of the stop determines the amount of liquid delivered by the hose. For example, if the amount delivered is too little, the stop 21 should be raised. If the amount is too great, stop 21 should be lowered.

A gate valve (not shown) can be inserted below 9, to serve as additional impedance, where the height of chamber 2 above nozzle 15 is so great that the range of adjustment of the shuttle stop 21 is insufficient.

Tank 1 is not shown with an air vent, and no air vent is intended for the preferred operation. During normal operation water will not spout out of the upper end of pipe 5. This is so because replacing air, passing from apertures 6 to reservoir 2 and then into tank 1 through the aperture in plate 3, mentioned above, has access to tank 1 only during momentary intervals when the level in 2 is sufficiently lowered.

Having thus described my invention, I claim:

1. An apparatus for delivering a substantially uniform amount of liquid, by gravity flow, comprising: a chamber connected to and in constant communication with a source of liquid, means providing an intake for air above the level of the liquid in the chamber and an outlet for liquid from the lower portion of the chamber, an upright tube connected at one end to said outlet to receive the liquid and at the other end to delivery conduit means for delivering the substantially uniform amount of liquid, a liquid faucet in the outlet of said delivery conduit, a buoyant shuttle of constant buoyancy in the upright tube, a valve seat in the lower part of the tube, and means providing a stop to limit the extent of upward movement of the shuttle, the shuttle being free to move downwardly with the downward rush

of liquid in the upright tube caused upon opening the liquid faucet, and to seat upon the valve seat to arrest the outflow of liquid past the valve seat, the shuttle being elongated longitudinally of the upright tube, the longitudinal surface of the shuttle being corrugated transversely to increase the friction between the shuttle wall and the surrounding by-passing liquid during the descent of the shuttle, the means providing an intake for air and an outlet for liquid being a conduit extending upwardly into the chamber and communicating through the upper face of the chamber with the atmosphere, said conduit having upper perforations permitting ingress of air into the chamber and lower perforations permitting flow of liquid from the chamber into the conduit and thence into the upright tube.

2. The apparatus of claim 1 in which a passage is provided between the lower end of the shuttle and the valve seat, in the lowermost posi-

10

tion of the shuttle, to prevent the holding of the shuttle against the seat caused by suction in the liquid delivery conduit.

3. The apparatus of claim 1 in which the means providing the stop includes a rod inserted into and adjustable longitudinally in the upright tube and the upright conduit.

HARRY L. STAFFORD.
